COMBUSTION PROMOTION DEVICE

Filed March 17, 1927

INVENTOR.
Albert French

BY

Philip S. McLean, ATTORNEY

UNITED STATES PATENT OFFICE

ALBERT FRENCH, OF BROOKLYN, NEW YORK

COMBUSTION-PROMOTION DEVICE

Application filed March 17, 1927. Serial No. 175,978.

The objects of this invention are to promote combustion of fuel in burners and furnaces and to provide effective means for this purpose in a form which can be readily applied and adapted to use in existing fuel burning systems.

In the accompanying drawing forming part of this specification, one simple, practical embodiment of the invention is illustrated. It should be understood, however, that the invention may be applied and used in other ways and in other structural forms without departure from the true spirit and broad scope of the invention as hereinafter defined and claimed.

Figure 1 is a sectional view of the fire door of a furnace showing two of the preheaters applied thereto, one appearing in plan and the other partly broken away and in section.

Figure 2 is a vertical sectional view as on line 2—2 of Figure 1.

The present invention comprises an air pre-heating device for spraying preheated air over a fuel bed to combine and burn with the unconsumed gases in the furnace chamber.

In the illustration this air preheater consists of a hollow open casting 3 having a substantially horizontal upper edge 4 on which rests a top or cap 5 having within its borders a dependent hollow projection 6 spaced from and forming with the inner wall of the hollow casting a substantially U-shaped channel 7. These cooperating walls are shown as shaped to produce a channel which is relatively flat in cross section and which widens toward the rear upwardly into a fan shape at 8 where there are located a number of substantially radially arranged tapered nozzles 9 extending approximately horizontally and having flaring mouths 10 at the outer ends of the same. These discharge nozzles are shown as formed in the body portion of the device practically at the upper end of the U-shaped channel. They may be precast or machined in the body or cover or partly in both and they form, with the fan shaped chamber at the upper end of the channel, means for spraying the air in fine streams over the entire fuel bed or flame.

The device is shown as supported on the

inner side of the fire door 11 as this provides a convenient mounting for supporting it at a proper level to mix the preheated air with the burning and unburned gases. It will be understood, however, that it may be supported in any other suitable way. The particular means of support shown consists of a nipple 12 extending through the door and entering a screw seat 13 at the upper end of the outer arm of the U-shaped channel. This nipple provides an inlet for the air and at the outside of the door serves as a support for the funnel shaped air receiver 14. This air inlet or rosette is shown equipped at the front with a rotatably adjustable vane or damper 15, which may be set to adjust the volume of air admitted.

Heat absorbing ribs or fins are shown on that portion of the body of the device which is exposed to the fire, at 16, the purpose of these being to aid in heating the U-shaped channel and fan shaped air discharge. The hollow projection of the cap is directly exposed to the fire and heats the entire top portion of the U-shaped passage. It will be noted that the U passage is formed with easy bends so that the incoming air is not choked back by being forced to change its direction at sharp angles. A natural inward flow is therefore produced without retarding it any more than is necessary to properly take up the heat. The expansion permitted by the fan shaped enlargement at the end of the U passage and the tapered nozzles cause the air to be sprayed with appreciable force and therefore to reach all portions of the fuel bed or flame.

By regulating the damper 15, the volume and flow of the combustion supporting air may be regulated to suit any particular requirements. This damper thus controls to an extent the force with which the preheated air is injected into the furnace chamber and may be used to determine this injector action. The damper or other supporting wall through which the nipple extends may be of double thickness, as customary in such structures and the screw-threads on the opposite ends of the same are preferably long enough to permit the air inlet member at

the outside to be screwed into abutting engagement with the outer face of the door and the air preheater to be screwed into abutting engagement with the inner face of the door so that both are firmly interlocked and supported fixedly in proper relation.

What is claimed is:

1. An injector preheater having a substantially U-shaped air inlet passage terminating in radially disposed air discharge nozzles, said nozzles being tapered toward their discharge ends and formed with flared exits.
2. An injector preheater having a substantially U-shaped air inlet passage with a fan shaped chamber at the discharge end thereof and substantially radially disposed nozzles in communication with said chamber, said nozzles being tapered from their discharge ends to accelerate the discharge of heated air.
3. An air preheater of the character disclosed, comprising a hollow body open at the top and a cap applied over and closing the open top portion of said body, said cap having a dependent hollow projection extending down into the hollow body and cooperating with the inner walls of said hollow body to form a substantially U-shaped channel within the hollow body and said hollow projection in the cap being open at the top and forming in the cap a heat absorbing cavity lying within the general outlines of the body, the channel formed within the body having an air inlet at one end and terminating in a discharge nozzle at the other end, the heat cavity within the cap being disposed in between said air inlet and discharge nozzle.

In witness whereof, I have hereunto set my hand this 7th day of March, 1927.

ALBERT FRENCH.
